US0D1110328S

(12) **United States Design Patent** (10) **Patent No.:** **US D1,110,328 S**
(45) **Date of Patent:** **** Jan. 27, 2026**

(54) **KEYBOARD WITH TABLET PROTECTIVE CASE**

(71) Applicant: **Electronic Silk Road (Shenzhen) Tech Co., Ltd., Shenzhen (CN)**

(72) Inventor: **Guichuan Zhou, Guangdong (CN)**

(**) Term: **15 Years**

(21) Appl. No.: **35/524,125**

(22) Filed: **Jan. 24, 2025**

(80) **Hague Agreement Data**

Int. Filing Date: **Jan. 24, 2025**

Int. Reg. No.: **DM/244308**

Int. Reg. Date: **Jan. 24, 2025**

Int. Reg. Pub. Date: **Feb. 28, 2025**

(30) **Foreign Application Priority Data**

Jan. 15, 2025 (CN) 202530025923.1

(51) **LOC (15) Cl.** **14-02**

(52) **U.S. Cl.**

USPC **D14/440**

(58) **Field of Classification Search**

(57) **CLAIM**

The ornamental design for a keyboard with a tablet protective case as shown and described.

DESCRIPTION

1. Keyboard with tablet protective case

1.1 : Front

1.2 : Back

1.3 : Left

1.4 : Right

1.5 : Top

1.6 : Bottom

1.7 : Perspective

1.8 : Perspective

1.9 : Perspective

1.1 : Perspective

1.11 : Perspective

1.12 : Perspective

1.13 : Perspective

1.1 is a front view of a keyboard with a tablet protective case showing my new design, shown in a closed position; 1.2 is a rear view thereof; 1.3 is a left view thereof; 1.4 is a right view thereof; 1.5 is a top view thereof; 1.6 is a bottom view thereof; 1.7 is a front, top and left side perspective view thereof; 1.8 is a front, bottom and right side perspective view thereof; 1.9 is a rear, top and right side perspective view thereof; 1.10 is a rear, bottom and left side perspective view thereof; 1.11 is a perspective view of the keyboard with a tablet protective case, shown in an open position; and 1.12 is another perspective view of the keyboard with a tablet protective case shown in reproduction 1.11; and 1.13 is a further perspective view of the keyboard with a tablet protective case shown in reproduction 1.11.

1 Claim, 13 Drawing Sheets
